HANDLE FOR COMBINED PAINT APPLYING TRIMMER AND EDGER

Donald Seip, Somerville, N.J., assignor to Red Devil Inc., Union, N.J.

Filed Dec. 9, 1971, Ser. No. 206,572

Term of patent 7 years

Int. Cl. D8—05

U.S. Cl. D64—18

FIG. 1

FIG. 2

FIG. 4

FIG. 3

FIG. 5

FIG. 6

FIG. 1 is a perspective view of a handle for a combined paint applying trimmer and edger showing my new design;

FIG. 2 is a view taken from one side thereof;

FIG. 3 is a view taken from the opposite side thereof;

FIG. 4 is a top plan view thereof;

FIG. 5 is a bottom plan view thereof;

FIG. 6 is a cross sectional view taken on line 6—6 in

FIG. 5.

I claim:

The ornamental design for a handle for combined paint applying trimmer and edger, substantially as shown.
